DESIGN FOR A BROOCH OR SIMILAR ARTICLE

Milton E. Brown, New York, N. Y.

Application July 27, 1940, Serial No. 93,961

Term of patent 3½ years

To all whom it may concern:

Be it known that I, Milton E. Brown, a citizen of the United States, residing at New York, in the city, county, and State of New York, have invented a new, original, and ornamental Design for a Brooch or Similar Article, of which the following is a specification, reference being had to the accompanying drawing, forming part thereof, wherein—

Fig. 2 is a side view of a brooch or similar article showing my new design.

While I have shown my new design embodied in a brooch or similar article, it is contemplated that the same may be embodied in somewhat similar articles of jewelry without departing from the spirit of my invention.

I claim:

The ornamental design for a brooch or similar article, substantially as shown and described.

MILTON E. BROWN.
